UNITED STATES PATENT OFFICE.

WILLIAM BOGGS RAILING AND CHARLES N. MAY, OF MECHANICSBURG, PA.

SAFETY-VALVE AND ALARM FOR STEAM-BOILERS.

SPECIFICATION forming part of Letters Patent No. 317,952, dated May 12, 1885.

Application filed December 23, 1884. (No model.

To all whom it may concern:

Be it known that we, WILLIAM B. RAILING and CHARLES N. MAY, both of Mechanicsburg, in the county of Cumberland and State of Pennsylvania, have invented a new and Improved Safety-Valve and Alarm for Steam-Boilers, of which the following is a full, clear, and exact description.

It is well known that safety-valves frequently stick and remain closed until the pressure in the boiler rises much higher than the point at which the valve is set, so that there is risk of explosion.

The object of our invention is to cause an alarm in case the safety-valve fails to open by the use of a pressure-detector in conjunction with an ordinary safety-valve, so constructed as to insure the invariable opening of the valve when the pressure reaches a given point.

To that end we combine a pressure-diaphragm and lever with a valve in such a manner that the valve is not closed or affected by the spring or weight of the lever, but is quickly opened when the lever is raised by the steam-pressure, as hereinafter described and claimed.

Reference is to be had to the accompanying drawing, forming a part of this specification, in which our improved device is shown by a sectional elevation.

A hollow case, A, forming a steam-chamber, is connected to a coupling, a, to which is also connected the steam-pipe B, by which the device is attached to the boiler, and to coupling a is also connected a pipe, C, that passes to a valve-chamber, D. The chamber D is sustained by a slotted post, b, through which passes the lever E, that is hung upon chamber A, and to the outer end of lever E is pivoted a rod or stem, d, that extends upward loosely through sleeve-nut e, that is screwed through the end of an arm, f, projecting from post b.

On stem d is a fast collar, g, forming a seat for a spiral spring, h, and above the spring is a loose washer, i, that bears against the lower end of sleeve-nut e, so that by screwing the nut up and down the tension of the spring and its pressure on lever E is regulated. There is a lock-nut on sleeve e, for locking it in place after the spring is set for the desired pressure.

Across the steam-chamber A is secured a

thin metallic diaphragm, k, and upon the diaphragm rests a plunger, l, that extends through the upper side of the chamber or case into contact with lever E at a point near its fulcrum. 55 The valve-chamber D has a seat, m, for the disk-valve n, whose stem extends upward into a guide-mortise, and the stem is fluted, so as to reduce the friction. Beneath valve n is a slide-pin, o, that extends through the lower 60 part of valve-chamber D to the lever E. A whistle, F, is connected to the outlet of chamber D.

When used on a boiler that is provided with an ordinary safety-valve, the lever E is to be set 65 by adjustment of the spring at the same pressure as the safety-valve. In case the latter fails to open when the pressure at which it is set is reached, the steam acting against diaphragm k raises lever E, thereby pushing pin o and 70 valve n upward and admitting steam to the whistle. The valve n opens easily and readily, and its form and arrangement are such that it is not liable to stick. When there is little or no pressure in the boiler, the lever E rests on 75 the bottom of the slot in post b, thereby relieving the diaphragm k of the weight. A drip-cock at p is for use in cold weather for drawing off water of condensation.

The device used as described constitutes a 80 sure detector in case the safety-valve fails to work.

By a suitable arrangement of the outlet the device may be used as a safety-valve.

There may be a weight used on lever E in 85 place of the spring shown.

Having thus described our invention, what we claim as new, and desire to secure by Letters Patent, is—

1. The safety-valve and alarm consisting of 90 the steam-chamber A, having an opening in its upper surface, the diaphragm k in said chamber, the plunger l, projecting loosely through the aperture of the chamber, and having its base resting on the said diaphragm, the 95 lever E, the pin o, valve-chamber D, and valve n, substantially as herein shown and described.

2. In a safety-valve and alarm, the combination, with the apertured post b, steam-chamber A, provided with the diaphragm k, and the loose 100 plunger l, of the lever E, pivoted to the said chamber, and projecting through the aperture

of the post, the stem *d*, and the adjustable spring *h*, substantially as herein shown and described.

3. In a safety-valve and alarm, the combination of stem *d*, nut *e*, spring *h*, and lever *E* with the steam-chamber *A*, having a slotted post, *b*, substantially as described.

4. In a safety-valve and alarm, the disk-valve *n* and pin *o*, the valve-case *D*, steam-

pipe *C*, and the lever *E*, combined substantially as described, whereby the valve is closed by steam-pressure and is independent of the weight of the lever, as set forth.

WILLIAM BOGGS RAILING.
CHARLES N. MAY.
